CARRIAGE OPERATING MECHANISM FOR
ACCOUNTING MACHINES

John T. Davidson, Oakwood, Ohio, assignor to
The National Cash Register Company, Dayton,
Ohio, a corporation of Maryland

Continuation of application Serial No. 143,641,
May 20, 1937. This application March 28, 1941,
Serial No. 385,770

4 Claims. (Cl. 197—65)

This invention relates to typewriting, accounting or bookkeeping machines having a laterally shiftable traveling carriage, and more particularly pertains to an impositive means for driving the carriage in its working direction with a high initial but decaying acceleration.

This application is a continuation of the application of John T. Davidson, Serial No. 143,641, filed May 20, 1937.

Because of the weight of traveling carriages on such described machines, a constantly applied driving force as heretofore used results in a low initial speed which increases the farther the carriage moves from rest position. This low initial and accelerating movement of the carriage results in two disadvantages; first, the movement of the carriage is sluggish at the beginning of its movement, wasting time on short spacing movements, and second, the carriage moves too fast at the end of a long spacing movement, causing a shock to the machine when suddenly stopped, accompanied by a rebound of the carriage in the reverse direction and consequent misalignment of the record material.

The present invention provides a hydraulic drive for such a traveling carriage that supplies a surplus force to move the carriage at the beginning of its movement from a state of rest, which surplus force is dissipated as the speed of the carriage increases to a determined maximum. Thus, at the outset of the carriage movement the acceleration is greatest and then decays toward zero. By adjustments of the drive, as provided, much greater force is impositively applied to the carriage at the beginning of its travel than is necessary to keep it in uniform motion, but as the speed of the carriage becomes sufficient, the force applied is automatically reduced to just enough to overcome friction and maintain the desired speed. In drives of an impositive nature heretofore known, notably the friction drive, the acceleration increases slowly during the entire carriage travel, because as the driving and driven parts decrease their relative motion the coefficient of friction becomes greater, thus causing a slow getaway and a high terminal velocity.

The impositive nature of applicant's drive allows the carriage to be moved in a reverse direction against the impositive drive in the ordinary manner to begin the tabulating movement anew. The stopping of the movement of the carriage, as well as its reverse movement, causes the hydraulic drive to build up potential energy, which not only prevents a rebound of the carriage as it

is stopped, but assures a rapid getaway at the next tabulating operation.

The time saved in initial acceleration permits lower terminal velocity of the carriage relative to the high average speed for the entire carriage travel.

Therefore, the principal object of this invention is to provide an impositive tabulating drive for the carriage of a machine of the class described capable of giving the carriage an acceleration to an optimum speed very quickly.

Another object of the invention is to provide a driving means for a carriage as described, whereby on moving from a state of rest the initial acceleration of the carriage decays quickly to zero.

Another object of the invention is to provide such a drive wherein there is no rebound after the carriage is stopped abruptly from full speed.

Another object of the invention is to provide a drive for a tabulating movement whereby the speed of the carriage is not permitted to exceed a certain limit which is reached very quickly.

Another object of the invention is to provide a carriage drive equally operable at all positions of the carriage to provide a quickly accelerated start, which acceleration quickly decays to zero.

Another object of the invention is to provide an impositive carriage drive wherein the major portion of the carriage travel is at a constant maximum speed.

With these and incidental objects in view, the invention includes certain novel features of construction and combinations of parts, the essential elements of which are set forth in appended claims, and a preferred form or embodiment of which is hereinafter described with reference to the drawings which accompany and form a part of this specification.

40 In the drawings:

Fig. 1 is a fragmentary rear elevation of the machine showing the driving motor and its connection to the impositive hydraulic device that drives the traveling carriage in its letter spacing or tabulating direction, and the connection of the motor to the clutch mechanism that returns the traveling carriage from tabulated positions to starting or initial position.

GENERAL DESCRIPTION

The present invention is shown embodied in the well known Ellis type of accounting machine fully illustrated and described in Letters Patent of the United States, No. 1,203,863, issued November 7, 1916, to Halcolm Ellis, Patent No. 1,819,084, issued August 18, 1931, to Emil J. Ens, and Patent No. 2,038,717, issued to Raymond A. Christian, October 9, 1935. Only the mechanism of the Ellis machine pertinent to the present invention will be described in detail in this specification, as reference may be had to the above patents for a full disclosure of the Ellis machine. The invention can be applied to any machine having a traveling carriage, and the Ellis type of machine is used only to illustrate the operation of the invention.

The Ellis machine is provided with a laterally shiftable traveling carriage supporting a platen roll adapted to present record material, carried thereby, to the printing mechanism. If desired, the Ellis machine may be equipped with a typewriter keyboard for typing various data upon the record material, and when so equipped, the machine is provided with an escapement mechanism operated by the typewriter keys for letter-spacing the traveling carriage. The escapement mechanism also holds the carriage against tabulating movement. Releasing the carriage for tabulation renders the escapement mechanism ineffective and moves a stop bar into the path of a series of stops, adjustably mounted on the carriage to correspond to the different columns of the record material. Tabulation of the carriage is terminated by one of the stops contacting the stop bar which is unlatched by the impact and immediately moves out of the path of the stop. The stop then contacts an escapement control plunger which is likewise unlatched by the impact and immediately causes the escapement mechanism to become effective to hold the carriage against further tabulation.

The traveling carriage has connected to the back thereof a horizontal rack which meshes with the driven member of an impositive fluid-operated, or hydraulic, drive similar to a gear pump, the driving member of said device being geared to the continuously operating motor which also drives the machine and the carriage return mechanism. This hydraulic drive forms an impositive connection between the operating motor and the traveling carriage that tends to constantly urge said carriage in its working or tabulating

direction. The fluid connection, between the elements of the hydraulic drive, permits the carriage to be held stationary or returned in the opposite direction to tabulating direction against

5 the action of said drive. When the carriage is held against tabulating movement, the hydraulic drive builds up a potential source of energy which firmly holds said carriage in tabulated position, and when the carriage is again released for tabulation this excess of energy causes the carriage to immediately and quickly get under way without the sluggishness apparent in other heretofore known methods of moving the carriage in a tabulating direction. As the carriage gets under 10 way, the pressure is reduced, causing said carriage to move at uniform speed. This decrease in acceleration of the carriage as its velocity increases allows a quick get-away without high terminal velocity and with a greater average speed than is possible with a spring or friction drive.

When movement of the traveling carriage is abruptly terminated, by the stop mechanism, hydraulic pressure is immediately built up in the drive, and this pressure restrains the traveling carriage against excessive rebound, irrespective of whether said carriage was tabulated a long or a short distance.

25 The hydraulic drive, in addition to driving the carriage in tabulating direction, also acts as a governor to control the speed of the tabulating movement to a fixed maximum.

Comparing the hydraulic drive, outlined above, 30 with a spring driven or friction driven traveling carriage, the spring or friction drives, on being released for movement, start slowly with their acceleration constantly increasing, gradually gaining in velocity until the movement is completed. When the traveling carriage is skip-tabulated through several intervening columnar positions, sufficient velocity and momentum are gained thereby to cause rebounding of the carriage when the movement thereof is abruptly terminated. This excessive rebounding slows up 35 the operation of the machine and sometimes causes the wrong operations, thereby hampering the work of experienced operators who have become exceedingly fast and proficient in handling particular business systems.

40 50 Mechanism pertinent to the present invention will now be described in detail.

DETAILED DESCRIPTION

Framework and traveling carriage

55 The mechanism of the machine embodying the instant invention is supported by a right frame 30 (Fig. 9) and a left frame 31 secured to a machine base 32 (Fig. 1), said frames being maintained in relation to each other by a crossframe 33, for the escapement mechanism, and a crossframe 34 (Fig. 5), which supports the tabulating mechanism, and various other crossframes, rods and shafts. The mechanism of the machine is 60 enclosed in a suitable case or cabinet 35 which is in turn secured to the base 32.

A traveling carriage 36 (Fig. 1) is supported 65 for horizontal shifting movement upon the case 35 by means of a rail 29 on the back thereof, in cooperation with a corresponding rail 37 mounted upon the case 35, both of said rails having matched angular grooves therein, which in cooperation with ball bearings (not shown) 70 permit free and easy movement of the traveling carriage while maintaining said carriage in ac-

curate alignment. The front of the traveling carriage is supported by rollers (not shown) mounted thereon in cooperation with a rail (not shown) secured to the case 35. The carriage 36 supports a platen roll 28 adapted to present record material, carried thereby, to the printing mechanism.

In figures, such as Fig. 9, where the framework is shown in phantom by dot and dash lines, where the dot and dash lines of such framework do not show behind the other parts, it indicates that such parts are in front of the framework.

The mechanism of the machine, the carriage return mechanism, and the carriage tabulating mechanism, are operated by a conventional type of continuously running electric motor 38 (Fig. 1) which is secured to the machine base 32. The shaft 39 of the motor 38 is geared to the driving member of the well known Ellis clutch mechanism, not shown herein but disclosed in U. S. Patent 1,601,102, issued September 28, 1926, to F. W. Bernau. The driven member of the clutch mechanism is connected by a link 40 (Fig. 9) to an arm 41 secured on the right-hand end of a main operating shaft 42 journaled in the frames 30 and 31.

Releasing the machine for operation causes the driven member of the clutch to be connected to the driving member whereupon the arm 41 and the shaft 42 are rocked first counter-clockwise, as viewed in Fig. 9, and then back to normal position through an approximate angle of 60 degrees, after which the driven member of the clutch is disconnected from the driving member in the usual and well known manner.

Tabulating drive of carriage

The traveling carriage 36 is driven in its letter spacing, working or tabulating direction, which is from the left toward the right, as viewed from the back of the machine (Fig. 1), by an impositive hydraulic drive instead of the conventional spring or friction mechanism. The hydraulic drive is actuated by the motor 38, and the shaft 39 of said motor is connected by various spiral gears (not shown) to a vertical shaft 43, journaled in a framework 44 secured to the motor framework. The shaft 43 drives the carriage return mechanism in a manner later to be described, and in addition has secured thereon a gear 45 which meshes with and drives a gear 46 secured on a vertical shaft 47 journaled in a bushing 48 fast in a plate 49 secured to the frame 44.

The shaft 47 is connected by a universal shaft 50 to a shaft 51, operating the hydraulic drive, journaled in a hydraulic drive housing 52 (Figs. 1, 2 and 3) and having secured on the upper end thereof a gear 53 which meshes with and drives a gear 54. The ends of the teeth of the gears 53 and 54 fit snugly in corresponding arcuate recesses which merge with each other and have connected therewith a D-shaped channel 55 (Fig. 2) which forms a circulating path for the viscous fluid which serves as an operating and a connecting medium for the hydraulic drive mechanism. The arcuate recess for the gear 54, in cooperation with the ends of the teeth of said gear, forms a bearing therefor.

Teeth in the periphery of the housing 52 (Figs. 1 and 2) mesh with a rack 56 having upturned ears with camming slots 57 therein, which engage rollers 58 mounted on brackets 59, secured to the framework of the carriage 36. A gasket

60 (Fig. 3), interposed between the housing 52 and a top plate 61, secured to said housing by screws 62, seals the fluid channel and the recesses for the gears, in said housing 52, against leakage. The housing 52 is rotatably mounted by means of a hub 63 (Figs. 1 and 3) thereof in cooperation with a bushing 64 secured in a plate 65 in turn secured to the rail 37. The hole in the hub 63 for the shaft 51 is counterbored and threaded to receive a packing washer 66 and its associated packing nut 67 which seal said hole against leakage.

The motor 38 drives the shaft 51 (Figs. 1 and 2) and the gears 53 and 54 in the directions indicated by the arrows causing the pump-like action of the teeth of said gears to force the fluid contained in the recesses for said gears and in the channel 55, in the direction indicated by the arrows in Fig. 2. Therefore it is readily seen that 10 a fluid connection is effected between the gears 53 and 54 and the housing 52, which tends to rotate said housing in the same direction (clockwise Fig. 2) as the gear 53. The amount of rotating action which is imparted to the housing 52 by the gears 53 and 54 is regulated by a metering screw 68 (Figs. 2 and 3) threaded in the channel 55. Decreasing the opening in the channel 55 increases the fluid pressure and causes the pump action of the gears 53 and 54 to exert increased rotating influence upon the housing 52.

The housing 52 in cooperation with the rack 56 tends to drive the carriage 36 in its letter spacing, working or tabulating direction, which is from left to right, as viewed in Fig. 1. When the traveling carriage 36 and the housing 52 are restrained against tabulating movement, the gears 53 and 54 simply circulate the liquid through the by-pass channel 55, creating pressure which is available immediately the carriage is released to cause a quick initial acceleration of the carriage which quickly decays to the speed set by regulating screw 68. Thus the great inertia of the resting carriage is overcome very quickly by the excess build up of pressure in the drive housing, no matter at what point the carriage is resting, which is an enormous improvement over drives which cause a slow get-away or drives requiring excessive carriage speeds.

Control of tabulating movement of traveling carriage

The tabulating movement of the traveling carriage 36 is controlled by means of the escapement mechanism shown in Fig. 7. When the typewriter keys are used the escapement mechanism is caused to operate step by step to letter-space the record material wound around the platen roll. The manner in which the typewriter keys operate the escapement mechanism will now be described.

Directing attention to Figs. 8 and 9, a typewriter key lever 69, which is representative of all the typewriter key levers, is pivoted on a rod 70 supported by the frames 30 and 31 and said key lever carries a stud 71, which cooperates with a camming slot in a type operating lever 72 pivoted on a rod 73, extending between the frames 30 and 31. The upper end of the lever 72 cooperates with a universal bar 74 mounted in slots in two forwardly extending arms of a yoke 75, said arms being pivoted on studs 76 in similar bent-over portions of a bracket 77, said bracket in turn being pivoted on studs 78 in extensions of the escapement frame 33. Rearward extensions of the yoke 75 (Figs. 7 and 8) support a pin 79

which fits loosely in a hole in a downward extension of a lever 80 free on a stud 81 secured in the frame 33.

Pivoted connected to an upward extension of the lever 80 is a bracket 82 having secured in a bent-over ear thereof one end of a rod 83, the other end of which fits loosely in a hole in an extension of a lever 84 free on a stud 85 fast in the frame 33. Also fulcrumed on the stud 85 is an escapement pawl 86 urged counter-clockwise by a spring 87 to normally maintain a tooth thereof in engagement with the teeth of an escapement ratchet 88 secured on the lower end of a vertical shaft 89 journaled in a bushing in the frame 33 (Fig. 8), and having secured on the upper end thereof a pinion 90 which meshes with a horizontal rack 91 secured to the framework of the traveling carriage 36. The spring 87 normally maintains an extension of the pawl 86 in contact with an eccentric 92 by means of which the tooth of said pawl is adjusted in relation to the teeth of the ratchet 88. The lever 84 is adjusted in relation to the yoke 75 by means of an adjustable collar 93 free on the rod 83 and its cooperating adjusting and locking nuts. A spring 94, tensioned between the pivot for the bracket 82 and an extension of the lever 84, normally maintains said extension in contact with the collar 93.

Depressing the key 69 (Fig. 9) rocks the lever 72 counter-clockwise, causing the upper end of said lever in cooperation with the universal bar 74 to shift the yoke 75 forwardly. Forward movement of the yoke 75 rocks the lever 80 (Figs. 7 and 8) clockwise, which movement, by means of the rod 83, rocks the lever 84 also clockwise, as viewed in Fig. 7, to cause the eccentric 92 on lever 84 to bear against the left end of the escapement pawl 86 to disengage the tooth of the escapement pawl 86 from the teeth of the ratchet 88. This frees the traveling carriage to the action of the hydraulic drive (Fig. 1) which causes said carriage to move toward the right, as here viewed, until a tooth of said ratchet 88 contacts a stop pawl 95 pivoted upon the lever 84. When the key 69 is released the yoke 75 is spring returned rearwardly to return the lever 80 (Fig. 8) counter-clockwise, which in turn permits the spring 94 (Fig. 7) to return the lever 84 counter-clockwise to move the stop pawl 95 out of the path of the teeth of the ratchet 88 and to move the escapement pawl 86 back into the path of said teeth to complete the escapement movement of the traveling carriage. When the traveling carriage is returned from tabulated positions to starting position, the ratchet 88 is reversely rotated, whereupon the teeth thereof ratchet under or by-pass the tooth of the escapement pawl 86.

Return movement of the traveling carriage 36 is terminated by means of a lug 96 on a return marginal stop 97 (Figs. 4 and 5), adjustably mounted on a stop bar 98, secured to the framework of the traveling carriage, in cooperation with the upper end of a stop plunger 99, slidably mounted in a recessed portion of the frame 34 and retained in said recess by means of screws 105 in cooperation with slots in said plunger 99.

Typewriter tabulating mechanism

The upper end of the plunger 99 (Figs. 4 and 5) is always in the path of the lug 96 to terminate return movement of the traveling carriage, in the manner explained above, and in addition, manipulative means is provided for rais-

ing said plunger into the path of tabulating stops, mounted on the stop bar 98, and for simultaneously disengaging the escapement mechanism, to permit the traveling carriage to tabulate under influence of the hydraulic drive mechanism until such movement is terminated by one of said stops contacting the plunger 99.

A spring 106 (Fig. 5) urges the plunger 99 upwardly to normally maintain a square stud 107, carried thereby, in contact with a rounded nose on an extension of a lever 108 pivoted on a stud 109 in the frame 34. A spring 110, which is strong enough to overcome the action of the spring 106, urges the lever 108 clockwise to normally maintain an extension 111 thereof in contact with a pad formed on the frame 34. The lever 108 positions the plunger 99 so that the upper end thereof is just beneath and out of the path of a lug 112 on a tabulating stop 113 adjustably mounted on the stop bar 98. The lever 111 has a nose 114 which underlies a hook-shaped extension of a lever 115 pivoted on a stud 116 in the frame 34. A notch 117 in another extension of the lever 115 engages a rearward extension of a lever 118 pivoted on a stud 119 (Fig. 9) in the frame 30. The lever 118 terminates in a fingerpiece 120 which is conveniently located to the right of the complement of typewriter keys, where it may be easily reached by the operator.

Depressing the lever 118 rocks the levers 115 and 108 counter-clockwise and clockwise, respectively, as viewed in Fig. 9, and clockwise and counter-clockwise, respectively, as viewed in Fig. 5, against the action of the spring 110 to lift the rounded nose of said lever 108 away from the stud 107 to permit the spring 106 to carry the plunger 99 upwardly into the path of the lug 112 on the stop 113.

The nose 114 of the lever 108 (Figs. 5, 8 and 9) overlies a stud 121 fast in a plunger 122 mounted to slide vertically in a slot in a pad on the frame 34. The plunger 122 has an aperture into which projects an extension of a bell crank 123 pivoted on a bracket 124 secured to the frame 34. The bell crank 123 is pivotally connected by a link 125 to one arm of a lever 126, free on a stud 127 in the frame 33. Another arm of the lever 126 is connected by a link 128 to an arm of a yoke 129 rotatable on a rod 130 supported by downwardly extending ears of the frame 33.

Depression of the lever 118 and consequent downward movement of the nose 114 of the lever 108, causes said nose in cooperation with the stud 121 to shift the plunger 122 downwardly to rock the bell crank 123 counter-clockwise, as viewed in Fig. 8, which in turn rocks the lever 126 and the yoke 129 clockwise. Clockwise movement of the yoke 129 causes an upwardly extending arm 131 thereof to engage an extension 132 (Fig. 7) of the escapement pawl 86 and rock the tooth of said escapement pawl out of engagement with the teeth of the escapement ratchet 88 to release the traveling carriage to the action of the hydraulic drive shown in Fig. 1, which immediately tabulates said carriage until the lug 112 (Fig. 5) on the stop 113 contacts the plunger 99. Releasing the manipulative lever 118 permits the spring 110 (Fig. 5) to return the lever 108 clockwise to move the upper end of the plunger 99 out of the path of the lug 112 and to permit a spring 133 (Fig. 8) to return the lever 126 and the yoke 129 counter-clockwise to render the escapement

mechanism effective to hold the carriage against further tabulating movement.

Automatic tabulating mechanism

In addition to the manual means for tabulating the traveling carriage, just described, there is also an automatic means, sometimes called the adding machine tabulating means, for tabulating the traveling carriage to align the different columns of the record material with the printing means. Ordinarily the automatic tabulating means functions immediately after the printing has been effected. However, the automatic tabulating means is subject to manual control by means of which it may be made to function at will without operating the machine. The automatic tabulating means is not in any way connected with or dependent upon the manual tabulating means just described, and may be properly termed a complete tabulating mechanism in itself, having its own set of stops and their associated control and stop bars.

Referring to Fig. 9, the arm 41, which operates the main shaft 42, is connected by a link 134 to an arm 135 connected to a printer operating shaft 136, journaled in the frame 30 and the printer framework. Initial movement counter-clockwise of the arm 41 moves the link 134 upwardly, causing an angular nose on a spring pulled hook 137 mounted thereon, to by-pass a stud 138 in a lever 139 loose on the stud 119, whereupon said hook 137 latches over said stud 138. Return movement clockwise of the arm 41 and consequent downward movement of the link 134 causes the hook 137 in cooperation with the stud 138 to carry the lever 139 downwardly in unison therewith.

The lever 139 (Figs. 5, 6 and 9) is slotted to receive one end of a lever 140 fulcrumed on a stud 141 in the frame 34, while another extension of said lever 140 underlies an arm of a lever 142 pivoted on a stud 143 in the frame 34. A spring 144 urges the lever 142 counter-clockwise, as viewed in Figs. 5 and 6, to normally maintain a raised surface thereof against a pad formed on the frame 34. Downward movement of the lever 139 rocks the lever 142 clockwise (Figs. 5 and 6) against the action of the spring 144, causing a pad on the bottom surface of said lever in cooperation with the stud 121 to shift the plunger 122 downwardly (see also Figs. 7 and 8) to disengage the escapement pawl 86 from the ratchet 88, in the manner explained earlier herein, to release the traveling carriage for tabulating movement under influence of the hydraulic drive shown in Fig. 1.

The lever 142 (Fig. 6) carries a stud 145, which extends through a slot in the lower end of a tabulating stop bar 146, the upper end of which fits loosely in a slot 160 in a built up portion of the frame 34. A torsion spring 147, in cooperation with a stud 148 in the bar 146, urges said bar upwardly in unison with the lever 142. Clockwise movement of the lever 142 causes a square stud 149 therein to move beyond the latching surface of a hook 150, free on a stud 152 in the frame 34, whereupon a torsion spring 151 urges said hook clockwise into the path of the stud 149 to obstruct counter-clockwise movement of the lever 142 when the hook 137 (Fig. 9) rides off the stud 138, near the end of return movement downwardly of the link 134. Clockwise movement of the hook 150, under influence of the spring 151, causes a hump 153 thereon to engage and rock the bar 146 counter-clockwise 75

into contact with the left wall (Fig. 6) of the slot 160.

The stud 148 (Fig. 5) extends through a slot in an escapement control bar 154, adjacent the stop bar 146, the upper end of which fits loosely in the slot 160 and the lower end of which is pivotally connected to a lever 155 fulcrumed on the stud 143. The lever 155 is similar in outline to the lever 142 and has a downwardly extending pad which cooperates with the stud 121 in exactly the same manner as said lever 142. A spring 156 urges the bar 154 counter-clockwise to normally maintain an undercut portion on the upper end thereof in contact with a square stud 157 in an arm 158 pivoted on a screw stud 159 in the frame 34 and said arm 158 is urged clockwise, by a spring 165, into contact with a stop stud. The stud 148 carries the bar 154 upwardly in unison with the bar 146 until a notch in said bar 154 moves beyond the stud 157, whereupon the spring 156 urges the bar 154 counter-clockwise to engage said notch with the stud 157 to obstruct downward movement of said bar 154.

Upward movement of the bars 146 and 154, in the manner explained above, moves their respective extensions 166 and 167 into the path of a stopping lug 168 (Figs. 5 and 6) on a tabulating stop 169 adjustably mounted on the stop bar 98. Near the end of the tabulating movement of the traveling carriage the lug 168 engages the extension 166 and carries the bar 146 clockwise into contact with the right-hand wall of the slot 160 in the frame 34, whereupon tabulating movement of the traveling carriage is terminated. This clockwise movement of the bar 146 rocks the hook 150 out of engagement with the stud 149 to release the lever 142 to the action of the spring 144, which immediately returns said lever and the bar 146 downwardly, to the position shown in Fig. 6. The projection 166 protrudes far enough beyond the projection 167, of the bar 154, to prevent the lug 168 from engaging said projection 167 when the bar 146 is rocked into contact with the wall of the slot 160.

Downward movement of the bar 146, as explained above, moves the projection 166 thereof out of the path of the lug 168 permitting the traveling carriage to tabulate a slight distance further until said lug 168 contacts the projection 167 of the bar 154, and rocks said bar clockwise to disengage the notch therein from the stud 157. Upon being thus released the bar 154 and the lever 155 are returned downwardly and counter-clockwise respectively to normal positions by a torsion spring 170 (Figs. 5 and 8) thereby releasing the plunger 122 and connected mechanism, to the action of the spring 133, which immediately rocks the yoke 129 counter-clockwise to move the arm 131 (Fig. 7) out of engagement with the extension 132 of the pawl 86, to permit said pawl to return into engagement with the teeth of the ratchet 88 to hold the traveling carriage against further tabulating movement.

In case the traveling carriage is accidentally or inadvertently returned toward starting position when the bars 146 and 154 (Figs. 5 and 6) are in upward positions, angular surfaces on the upper ends of said bars permit the lug 168 to cam said bars downwardly until said lug by-passes said bars. The slot in the lower end of the bar 146 permits such downward movement thereof, independently of the lever 142, and the spring-pulled arm 158 permits such downward movement of the bar 154 and after the lug 168 has by-passed

said bars they are immediately returned upwardly to effective positions.

In addition to the automatic means described above, manual means is also provided for rocking the lever 139 (Fig. 9) downwardly to render the tabulating mechanism effective. This means includes a tabulating key 100, located on the right-hand side of the adding machine keyboard and urged upwardly by a spring not shown. The key 100 has in its lower end a stud 101 which cooperates with a shoulder 102 on an arm 103 pivoted on the lever 139 and urged counter-clockwise or forwardly by a spring 104 to normally maintain a bent-over ear thereof in contact with the lower surface of the lever 139.

Depressing the tabulating key 100 causes the stud 101, in cooperation with the shoulder 102, to rock the lever 139 downwardly or clockwise to cause the traveling carriage to tabulate in the manner explained above. Before the key 100 is fully depressed the stud 101 rides off the shoulder 102 permitting the lever 139, which has been carried a slight distance beyond set position, to be spring-returned to set position to move the shoulder 102 above the stud 101. When the tabulating key 100 is released it is spring-returned upwardly, whereupon the stud 101 by-passes the shoulder 102, causing the arm 103 and the stud 101 to come to rest in proper relation to each other, as shown in Fig. 9.

Carriage return mechanism

Mechanical means is provided for returning the traveling carriage from tabulated position to starting or initial position. When the traveling carriage reaches the end of its tabulating movement the carriage return mechanism is automatically rendered effective and returns said carriage immediately to starting position against the urge of the hydraulic drive. In addition to the automatic means, manual means is provided for rendering the carriage return mechanism effective to return the traveling carriage from any tabulated position to initial or starting position.

Referring to Figs. 1 and 2, the shaft 43 is connected by a universal shaft 171 to a short vertical shaft 172 opposite ends of which are journaled in parallel cross members of a frame 173 secured to the case 35. Secured on the upper end of the shaft 172 is a disc 174 having a plurality of clutch teeth adapted to cooperate with similar teeth on a carriage return gear 175 free on the shaft 172 and meshing with the rack 56. A downwardly extending hub of the gear 175 has an annular groove which embraces the rounded end of a shifting lever 176 free on a stud 177 in the frame 173. The gear 175 has two positions: a disengaged position as here shown and an engaged position, in which the clutch teeth thereof are engaged with the clutch teeth of the disc 174, and said return gear 175 is retained in either of its positions by means of a nose 178 on the lever 176 in cooperation with a spring-pulled retaining pawl 179 fulcrumed on a stud in the frame 173.

A closely coiled spring 180 connects the lever 176 to a beam 181 pivoted on a stud 182 in the case 35 and having a left-hand extension which overlies the end of a lever 183 (see also Fig. 4) pivoted on a bracket 184 secured to the case 35. The forward end of the lever 183 is straddled by the bifurcated lower end of a plunger 185 free in a vertical hole in the case 35, the upper end of said plunger being rounded to facilitate cooperation with a camming lug on a carriage re-

turn bar 186 mounted for horizontal sliding movement in a groove in the case 35.

When the traveling carriage nears the end of its tabulating movement, a downward projection on a carriage return arm 187 (Fig. 4) pivoted on a stop 188 adjustably mounted on the bar 98, engages an upturned portion 189 of the bar 186 and slides said bar toward the left, as here viewed, causing the camming lug thereon, in cooperation with the rounded upper end of the plunger 185, to rock the lever 183 counter-clockwise. Counter-clockwise movement of the lever 183 rocks the lever 181 clockwise, as viewed in Fig. 1, which, by means of the spring 180, rocks the lever 176 counter-clockwise to shift the clutch teeth on the return gear 175 into engagement with the corresponding clutch teeth on the return disc 174.

The continuously running motor 38 (Fig. 1) drives the clutch disc 174 in the direction indicated by the arrow, and as the return gear 175 is clutched thereto it necessarily rotates in unison therewith and in cooperation with the rack 56 returns the traveling carriage 36 from tabulated position to starting position, or from right to left as viewed in Fig. 1, and from left to right as viewed in Fig. 4. The automatic return of the carriage may be rendered inoperative by moving the arm 187 clockwise (Fig. 4) until the projection thereof is out of the path of the upturned portion 189 of the bar 186.

Return movement of the traveling carriage is terminated by the lug 96 on the marginal stop 97 coming in contact with the plunger 99 whereupon continued rotation of the return gear 175 (Fig. 1) shifts the rack 56 toward the left independently of the traveling carriage 36 and against the action of a spring (not shown). It will be recalled that the rack 56 is guided in its sliding movement by the camming slots 57, in cooperation with rollers 58. Near the end of the independent movement of the rack 56 the contour of the slots 57 in cooperation with the rollers 58 shifts said rack downwardly, causing the teeth therein, in cooperation with a flange 190, integral with the return gear 175 and adjacent the teeth of said gear, to shift said gear downwardly to disengage the clutch teeth thereof from the clutch teeth of the return disc 174 to terminate return movement of the traveling carriage. After the return gear is thus disengaged the rack 56 is spring-returned to the position shown in Fig. 1. To prevent unnecessary wear of the nose of the lever 176, the face of the flange 190 bears on a pin 191 when the return gear 175 is in disengaged position.

In addition to the automatic return of the traveling carriage, the bar 186 (Fig. 4) has a forwardly extending fingerpiece 192, by means of which said bar 186 may be manually shifted toward the left to cause the traveling carriage to be returned from any desired tabulated position. The traveling carriage return mechanism may also be set in motion manually by means of a lever 193, the forward end of which extends through an opening in the case 35 and terminates in a fingerpiece 194, which is conveniently located in relation to the typewriter keyboard, while the rearward end of said lever is pivotally mounted adjacent the lever 183 on the bracket 184. A spring 195 normally retains the lever 193 in its upward position, as here shown. Depressing the lever 193 causes a hook-shaped portion 196 thereof, in cooperation with a stud 197 in the lever 183, to rock said lever counter-

clockwise, as viewed in Fig. 4, to render the carriage return mechanism operative, in the manner explained above.

During return movement of the traveling carriage 36 (Fig. 1) the housing 52 of the hydraulic drive mechanism is rotated in an opposition direction to the shaft 51, which is possible due to the fluid connection between said housing and said shaft.

From the foregoing description it is apparent that the salient feature of the instant invention is the hydraulic drive applied to a tabulating carriage, which replaces the heretofore used conventional spring or friction disc actuated mechanism for driving the carriage in its working or tabulating direction, said hydraulic drive being actuated by a continuously running motor which also drives the carriage return mechanism and the machine operating mechanism. The improvements resulting from the use of applicant's hydraulic drive in combination with a tabulating carriage, as described, are high initial speed, high average speed for short or long tabulations, and moderate terminal velocity on long tabulations.

While the form of mechanism herein shown and described is admirably adapted to fulfill the objects primarily stated, it is to be understood that it is not intended to confine the invention to the one form or embodiment herein disclosed, for it is susceptible of embodiment in various forms all coming within the scope of the claims which follow.

What is claimed is:

1. In a machine of the class described including a movable carriage and releasable means for holding the carriage from movement in one direction, the combination of a motor; a gear pump including driving and driven members and a throttled passage and acting to pump a fluid through said passage, resistance to flow offered by said passage creating a back pressure tending to drive said driven member; driving connections between said motor and said driving member; and driving connections between said driven 45

member and said carriage, whereby, when the motor is operating and the carriage held at rest by said releasable means, potential energy is generated by said pump tending to move the carriage which energy decreases as said carriage moves when released.

2. In a machine of the class described including a movable carriage and releasable means for holding the carriage from movement in one direction, the combination of a motor; a pump including driving and driven members and a throttled passage, said driving member pumping a fluid through said passage and the back pressure generated by the resistance to flow of said passage tending to move said driven member; drive connections between said motor and pump driving member; and drive connections between said driven member and the carriage, whereby potential energy is created by operation of the motor tending to move the carriage from a position of rest, which energy is decreased by movement of the carriage.

3. In a machine of the class described including a movable carriage and releasable means for holding the carriage against movement in one direction, the combination of a motor; a fluid-pressure generator driven thereby; a carriage-driving member actuated by the fluid pressure developed in said generator; and driving connections between said member and said carriage, whereby pressure tending to drive said carriage from a position of rest is built up when the carriage is held at rest and the motor is operating.

4. In a machine of the class described including a movable carriage and releasable means for holding the carriage against movement in one direction, the combination of a motor; and driving connections between said motor and said carriage including a fluid coupling of a type permitting slip but developing potential energy during slip, which energy is available to start said carriage from rest, development of said energy being decreased by movement of the carriage.

JOHN T. DAVIDSON.
